DRIVE MECHANISM

Lawrence C. Tober, Fresno, Calif., assignor, by direct and mesne assignments, to The Vendo Company, Kansas City, Mo., a corporation of Missouri

Filed Oct. 17, 1955, Ser. No. 541,007

10 Claims. (Cl. 192—15)

The present invention relates to a drive mechanism and more particularly to a mechanical power linkage adapted to transmit power therethrough in a predetermined direction and to resist transmission of power in a reverse direction. It is best visualized as a mechanism for interconnecting a source of power and a driven member so as to communicate motivating force from the source of power to the driven member, to resist operation of the driven member independent of the source of power, and to preclude operation of the source of power by the driven member.

The instant invention is especially adapted for use in vending machines as disclosed in the prior co-pending application of Spencer L. Childers and Lawrence C. Tober S.N. 465,779, filed November 1, 1954, now Patent No. 2,877,924, granted March 17, 1959, and the prior co-pending application of Spencer L. Childers S.N. 489,319, filed February 21, 1955, and issued as Patent No. 2,836,326 on May 26, 1958. Therefore, in order more fully to appreciate the subject invention, a brief explanation of the vending machine of these prior applications is offered for illustrative convenience.

The vending machines referred to above provide cabinets in which are mounted magazines defining compartments each holding a pair of vertical stacks or columns of vendible articles in vertically staggered overlapping relation with the article in one stack in underlying supporting relation to articles thereabove. Although it has long been known to stack vendible articles in this manner as typified by the patent to Hoffman No. 1,205,094 and the patent to Hoopes et al. No. 1,711,021, the vending or control mechanisms have received much attention in efforts to provide simpler, more dependable, accurate and economical operation.

The vending machines of the applications cited provide rocker cradles having article engaging fingers. The cradles are rockably mounted in the compartments in supporting relation to the bottles thereabove and in positive driven connection to a control mechanism manually operated to rock the cradles to and from article vending positions. It is significant that in both of these machines of the applications noted, positive drive is necessary to vend an article.

This is in contrast to certain vending machines of the prior art which retain articles in vertically staggered overlapped stacks but which employ article support means in the form of pivoted pendent levers or bails movable between opposite positions in supporting engagement with a lowermost article in a column of articles thereabove. Such a lever is generally releasably held in alternate such positions and when released, the articles drive the lever from a position under one column to a supporting position under the other column and in so doing permit vending of an article. Obviously, unless carefully controlled, such an arrangement enables the articles to drive the lever back and forth in rapid succession completely to vend all of the articles, an undesirable operation referred to in the trade as "jack potting." The present invention is suit-

2

able for use in both types of vending machines and in both insures positive dispensing, precludes jack potting, effects precise control during all vending phases, avoids reliance on the aggregate weight of articles yet to be dispensed as the motivating force, and operates with absolute uniformity regardless of the extent of reserve articles.

Accordingly, an object of the present invention is to provide a drive mechanism or linkage adapted to establish driving interconnection between a source of power and a driven member for motivating the driven member upon operation of the source of power but to preclude independent motivation of the driven member and driving of the source of power by the driven member.

Another object is to provide a drive mechanism particularly adapted for use in a vending machine in which articles to be vended are releasably retained in staggered, overlapping, vertical stacks, which mechanism provides positive, accurately controlled retaining and dispensing of such articles.

Another object is to prevent uncontrolled self-emptying of a vending machine by mere imposition of the weight of articles to be vended on article support and vending control members therefor.

Another object is to provide a drive mechanism for a vending machine which includes a driven vending control shaft operable to vend an article upon predetermined rotation of the shaft, which mechanism is locked against such rotation of the shaft except by positive manipulation of a prime mover therefor in a predetermined direction.

Another object is to provide a brake having controlled constricting engagement around a shaft normally precluding rotation of the shaft and releasable to permit rotation of the shaft.

Another object is to provide an arrangement for releasing the brake of the foregoing paragraph which is adjustable to accommodate brakes of varying characteristics.

Other objects are to provide improved elements and arrangements thereof in a device of the character and for the purposes set forth.

These and other objects will become more fully apparent upon reference to the following description.

In the drawings:

Fig. 1 is a horizontal section of a vending machine embodying the principles of the present invention.

Fig. 2 is a somewhat enlarged fragmentary vertical section taken on a plane having the position represented by line 2—2 of Fig. 1.

Fig. 4 is a longitudinal section taken diametrically through the drive mechanism shown in Fig. 3 along a plane displaced 90° from the plane viewed in Fig. 3.

Fig. 5 is a transverse section taken on line 5—5 of Fig. 3.

Fig. 6 is a transverse section taken on line 6—6 of Fig. 3.

Fig. 7 is a transverse section taken on line 7—7 of Fig. 3.

Fig. 8 is a fragmentary transverse section taken on line 8—8 of Fig. 3.

Referring more particularly to the drawings:

A vending machine constituting an illustrative environment for the present invention is generally indicated by the numeral 10 in Fig. 1 and has an insulated cabinet 11 providing an interior compartment 12 adapted to be refrigerated in a manner not shown but believed well under-

stood in the art. The cabinet provides an opening 13 for obtaining access to the compartment. Additionally, the cabinet has a pair of insulated side walls 14, a rear wall 15, and top and bottom walls, not shown.

An insulated door 19 is pivotally mounted on the cabinet 11 by hinges 20 provided for the purpose and is adapted to be locked in closed position in any suitable manner. A seal 21 is positioned between the door and the cabinet for sealing the compartment 12 and maintaining refrigeration therein when the door is closed. The door provides an insulated wall 22, an outer sheet metal wall 23, and a space 24 between the insulated wall and the sheet metal wall.

A service door 30 is mounted by means of hinges 31 on the sheet metal wall 23 of the door 19 over an opening therein. The service door has a recess 32 therein for a purpose subsequently to be described. Although forming no essential part of the present invention, a coin control mechanism 33 is mounted on the insulated wall 22 within the space 24. As is well known, the coin mechanism preconditions the vending machine for vending operation upon receipt of a coin or coins of predetermined acceptable denomination.

A support frame 40 provides a front wall 41, a rear wall 42 and a pair of side walls 43 interconnected in substantially rectangular relation. A pair of angle brackets 44 are individually connected to the side walls of the support frame and are releasably connected to the cabinet 11 by suitable bolts 45 which mount the support frame in the compartment 12 of the cabinet. A pair of intermediate walls or partitions 46 are mounted between the front and rear walls transversely disposed in substantially parallel relation to the side walls.

The support frame 40 thus provides a plurality of vendible article receiving compartments for descriptive convenience hereinafter referred to as a left compartment 50 and a right compartment 51 having lower discharge ends. The intermediate walls 46 also provide a central space 52 therebetween. The rear wall 42 has a pair of arcuate or kidney-shaped slots 53 at lower portions thereof so as to provide passageways into the compartments.

A pair of vertically disposed channel members 58 are arranged in each of the compartments 50 and 51 and include back portions 59 rigidly secured to the rear wall 42, side portions 60 forwardly extended in spaced substantially parallel relation, and spaced in-turned flanges 61.

A pair of rocker cradles or gates 66 are individually mounted in substantially horizontal positions in the support frame 40 adjacent to the discharge ends of the compartments 50 and 51. Each cradle provides a pair of substantially parallel end plates 67 having horizontally extended rocker pins 68 rotatably journaled respectively in the front and rear walls 41 and 42 of the support frame. The end plates are spaced apart a sufficient distance to permit passage of the articles to be vended therebetween. Control pins 69 are extended from the rear end plates through their respectively adjacent slots 53 for movement therein to limit rocking motion of the cradles to predetermined desired limits. Each cradle provides a pair of spaced angulated bars 70 interconnecting the end plates and spaced apart a distance sufficient to permit passage of an article to be vended therethrough. Finger plates 71 are releasably secured by screws 72 to the angulated bars and provide upwardly extended article engaging fingers 73.

The structure described thus far has its counterparts in the related co-pending applications cited above and is repeated herein to facilitate understanding of the operation and use of the present invention to which detailed reference is now made.

With particular reference to Figs. 3 and 4, a bearing sleeve 76 is extended through the rear wall 42 of the support frame 40 and secured thereto by bolts 77. The bearing provides a shoulder 78 and a forwardly extended

portion 79 diametrically reduced from the shoulder. A vending control shaft 85 is rotatably journaled in the bearing sleeve 76 and provides a rear end 86 extended rearwardly of the rear wall 42 and a forward end 87. The vending control shaft has an annular collar 88 adjacent to the forward end thereof in abutment with the extended portion 79 and providing a longitudinally extended groove 89. The extended portions of the bearing and the collar have substantially cylindrical peripheries of substantially the same diameter.

10 A flanged eccentric disc 95 is fitted on the rear end 86 of the vending control shaft 85 and provides a rear mounting sleeve 96 secured to the shaft by a pin 97. A pair of tapered levers 98 provide lower drive ends 99 individually pivotally connected to the control pins 69 associated with the cradles 66 and substantially circular upper openings 100 rotatably fitted in juxtaposed relation on the eccentric disc.

15 A ratchet wheel 105 is fitted on the mounting sleeve 95 and secured to the eccentric disc 95 by a bolt 106. The ratchet wheel provides a periphery having a plurality of substantially equally spaced ratchet teeth 107 positioned in substantially right angular relation to each other. A U-shaped pawl 108 is pivoted to the rear wall 20 42 by means of a pivot pin 109 and is adapted to ride on the periphery of the ratchet wheel for periodic engagement with the teeth thereof thereby to restrict rotation of the vending control shaft 85 to one direction only, such direction being clockwise as viewed in Fig. 2.

25 30 A brake release bracket 115 provides a substantially U-shaped portion having a fractionally-circular mounting flange 116 (Fig. 8) rotatably fitted on the bearing shoulder 78, a fractionally-circular adjusting plate 117 having a plurality of apertures 118 lying along an arcuate path 35 (Fig. 7) and a connecting plate 119 (Fig. 4) interconnecting the mounting and adjusting plates providing a slot 120 adjacent to the mounting plate. The brake release member also has a substantially L-shaped portion providing an adjusting plate 121 rotatably fitted on the 40 control shaft 85 against the adjusting plate 117. The adjusting plate 121 provides an arcuate slot 122 and a bolt 123 extended through the slot into a selected aperture 118 together with suitable lock washers, as 124, are provided for adjustably connecting the adjusting plates. 45 The L-shaped portion further has a tapered actuating arm 125 perpendicularly extended from its adjusting plate in substantially parallel relation to the vending control shaft.

50 55 A helical coil spring brake 130 is wound in overlapping relation around the bearing sleeve extension 79 and the annular collar 88 of the vending control shaft 85. The spring brake has a rear end bent radially outwardly therefrom and releasably extended through the slot 120 in the connecting plate 119 of the brake release member 115. The spring brake also has a forward end 132 radially inwardly extended into the groove 89 of the annular collar. As will be soon apparent the end 132 need not necessarily be inserted in the groove 89 for operation of the brake but such association is found to be an assembling convenience.

60 65 A clutch mechanism, generally indicated by the numeral 140, includes a substantially cylindrical driven clutch member or pawl 141 having a concentric forward opening 142 and an extended sleeve 143 securely mounted on the forward end 87 of the shaft 85 by a pin 144. The driven clutch member provides a pair of forwardly extended diametrically opposed camming pegs 145.

70 75 A flanged bearing plate 150 is mounted between the intermediate walls 46 of the support frame 40 in any suitable manner and a drive shaft 151 is journaled in the bearing plate and provides a rearward end 152 extended within the opening of the driven clutch member 141 and a forward end extended through the bearing plate on the forward side thereof. The clutch mechanism 140 also includes a drive clutch member or ratchet

wheel 153 constituting a camming plate slidably and rotatably mounted on the drive shaft by a substantially U-shaped connecting plate 154 having longitudinally extended arms connected thereto. The drive clutch member provides a plurality of peripherally located tongues 155 constituting camming ramps struck forwardly outwardly from drive member 153 and leaving thereby arcuate slots 156. Four slots and tongues are provided in the illustrated embodiment and these are arranged in diametrically opposed pairs. The connecting plate 154 has a pair of longitudinally extended slots 157. A pin 158 is transversely mounted in the drive shaft outwardly slidably engageable in the slots of the connecting plate thereby to enable turning of the drive clutch member by the drive shaft. A spring 159 is fitted around the drive shaft between the pin 158 and the drive clutch member for urging the drive member into engagement with the driven clutch member 141.

A receiver plate 165 is mounted on the forward end of the drive shaft 151 and provides a pair of outwardly extended arms 166 having axially aligned arcuate notches 167 therein. An operating shaft 170 is rotatably mounted in the door 19 and provides an inner end having a key 171 transversely mounted thereon adapted releasably to fit in the notches 167 of the receiver plate 165. A manipulating handle 172 is secured to an outer end of the vending operating shaft and located in the recess 32 of the service door 30. The operating shaft is operably associated with the coin control mechanism 33 in a manner well known in the art. It is only necessary to note that upon receipt of a coin or coins of suitable denomination by the coin control mechanism the shaft 170 is released to be rotated a predetermined angular amount by depressing the manipulating handle.

A plurality of vendible articles, such as bottles 175, are arranged in the compartments 50 and 51 in a pair of vertical columns in vertically staggered relation with the articles in one column being in supporting relation to articles upwardly adjacent thereto in the adjacent column. The bottles provide necks, not shown, rearwardly extended and slidably fitted between the inturned flanges 61 of the respective channel members 58. It is believed evident that the spacing between adjacent walls 43 and 46 defining each of the compartments is less than the maximum combined width of a pair of articles to be vended so that consecutive articles in each compartment are stacked closely adjacent to each other in the manner described.

Operation

The operation of the embodiment of this invention is believed to be apparent and is described at this point. The vending machine 10 is initially loaded with bottles 175, as indicated in Fig. 2, or other vendible articles, and the door 19 closed and locked in position against the cabinet 11. In order to obtain a bottle, or bottles, from the machine, a coin or coins of suitable denomination are inserted in the coin control mechanism 33, in a manner well known in the art, thereby releasing the operating shaft 170 for a predetermined limited angular rotation by depressing the manipulating lever 172. As seen in Fig. 1, the receiver plate 165 is turned when the operating shaft is rotated and this motion is transmitted through the drive shaft 151 to the clutch mechanism 140 which is normally engaged, as illustrated.

Further, the actuating arm 125 is normally extended through one of the slots 156 displaced 90° from the slots receiving the pegs 145. The relative location of the pegs and the actuating arm in their respective slots is such that as the drive clutch member 153 is rotated the actuating arm is engaged by the drive clutch member prior to engagement of the pegs therewith. Thus the clutch mechanism provides for delayed interconnection of the vending control shaft 85 and the drive shaft 151 incident to rotation of the drive shaft. This in-

sures release of the spring 130 prior to driving connection between the shafts 85 and 151 so that rotatable movement can be imparted to the vending control shaft by the drive shaft.

- 5 While discussing the action of the brake release member 115 on the brake spring 130, it is to be noted that the plates 117 and 121 are to be angularly adjusted relative to each other by the bolt 123 to correspond to the characteristics of the spring 130 being employed. Thus, 10 for example, if the spring fits too tightly or too loosely on the bearing sleeve 76 and the annular collar 88 of the vending control shaft 85 or if the springs employed in such devices have opposite ends in various angular relation, it may be necessary to rotate the adjusting plate 15 121, relative to the adjusting plate 117 to accommodate such variances.

In any event, with the brake spring 130 thus relieved from tight constriction around the bearing sleeve 76 and the shaft 85, the latter is released for rotation through 20 the engagement of the drive clutch member 153 with the driven clutch member 141, as will be understood. This turns the eccentric 95 in a clockwise direction, as seen in Fig. 2, to actuate the levers 98 and thereby to oscillate the cradles 66 by movement of the pins 69.

- 25 Rotation of the control shaft 85 is permitted only through a predetermined angle, this being 90° in the illustrated embodiment. The coin control mechanism 33 limits rotation of the drive shaft 151 to a slightly greater extent permitting a predetermined initial increment of travel for unlocking purposes before the control shaft is moved. At the precise instant that the control shaft 85 has turned through 90° during a single depression of the manipulating lever 172, at least one of the cradles 30 66 has moved into a position to discharge the lowermost bottle 175 in its compartment 50 or 51. Simultaneously the point of contact of the article engaging fingers 73, which are then upwardly extended, with the lowermost bottle in the stack of bottles thereabove, hereinafter referred to as the bottle-finger contact point and 35 indicated at 180 in Fig. 2, is brought into alignment with a line drawn from the center of such lowermost bottle to the center of the rocker pins 68 of the cradle under consideration. This line is hereinafter referred to as the support line and is indicated at 181 in Fig. 2. This 40 relationship is illustrated in Fig. 2 by the cradle in compartment 50. Likewise at this exact moment, the pawl 108 engages a tooth 107 on the ratchet wheel 105 to lock the control shaft against reverse rotation.

45 Since the manipulating lever 172 cannot be rotated 50 any farther in a clockwise direction and since a bottle 175 has been vended, the lever 172 is released so that it can move back to its upper position. The end 131 of the spring brake 130 then urges the spring release member 115 in a counterclockwise direction, as seen in Fig. 55 5, to rotate the drive clutch member 153 in a counterclockwise direction. This slides the ramps 155 over the pegs 145, which are now held stationary by the pawl 108 until the pegs slip into slots 156 displaced 90° in a clockwise direction circumferentially of clutch member 153 60 thereby preconditioning the clutch mechanism 140 for the next depression of the manipulating lever.

65 Specifically, each of the cradles 80 rotates through a cycle of operation which, with reference to Fig. 2, includes four positions, corresponding to each 90° of rotation of the vending control shaft 85. Thus each cradle starts, for example, in a middle substantially horizontal position, rotates clockwise to a position inclined to the right, then rotates counterclockwise back to a middle 70 position, then continues in a counterclockwise direction to a position inclined to the left, and then rotates in a clockwise direction to return to a middle position. In all of the positions of the rockers, the article engaging fingers 73 on one or the other or both sides of the cradles 75 are in supporting engagement with the lowermost bottle

in the stacks of bottles in their respective compartments 50, or 51. When the cradles move to either of their left or right inclined positions, they are disposed to permit the lowermost bottle to pass therethrough for delivery for customer access exteriorly of the vending machine 10. Further, in either of said left or right inclined positions, the upwardly extended article engaging fingers are in engagement with the lowermost bottle next adjacent above the bottle being vended in the stack of bottles in their respective compartments.

Considering a cycle of operation, when the manipulating lever 172 is depressed, as above described, to rotate the cradles 66, and assuming that the cradles start from a position as shown in Fig. 2, the cradle of compartment 50 rotates in a counterclockwise direction to a middle position with the right fingers 73 supporting the lowermost bottle 175 in the compartment. Simultaneously, the cradle in compartment 51 moves from the middle position in a counterclockwise direction to a position tilted to the left whereby the lowermost bottle 175 in the left stack of bottles falls through the cradle and thus is vended. At the same time the right article engaging fingers move into supporting engagement with the lowermost bottle in the right stack of bottles in compartment 51.

During the next depression of lever 172, the cradle 66 in compartment 50 moves to a position tilted to the right to vend the lowermost bottle previously supported and to bring the left fingers into supporting engagement with the lowermost bottle in the left stack. Concurrently, the cradle in the compartment 51 moves in a clockwise direction to a middle position still having the fingers 73 in supporting engagement with the lowermost bottle in the right stack of bottles in compartment 51. It is believed evident that successive depression of the lever are effective to rotate the cradles through their successive positions as above described alternately to discharge a bottle from the compartments and that only one bottle is discharged from only one of the compartments during a single depression of the lever.

Under normal operation, as explained above, a single depression of the manipulating lever 172 moves at least one of the cradles 66 into such a position that the bottle-finger contact point 180 is in alignment with the bottle center-rocker pin center connecting line 181, or is slightly to the left of such line, as viewed in Fig. 2. Thus, the weight of all of the bottles in compartment 50 acts as a resultant force imposed directly through the pivot axis of the cradle along the line 181. The lowermost bottle tends to wedge between the upwardly extended fingers and the adjacent wall 46 so that no amount of weight imposed on such lowermost bottle is effective to turn the cradle in a clockwise direction, this being the direction in which the cradle must move in order to reach its next vending position.

Further, the weight of the bottles 175 in compartment 51 bearing on the fingers 73 at the left of the cradle 66 therein is ineffective to turn such cradle and thereby the cradle in compartment 50 through the interconnecting linkages. The reason for this is that, as explained above, the cradle in compartment 50 resists clockwise rotation because of relationship of the bottle contact point 180 and the line 181 and also because of the friction between the pins 69, levers 98 and eccentric 95. With this in mind, therefore, it will be understood that during normal operation of the vending machine the bottles cannot drive the cradles successively to their vending positions merely by imposition of the weight of the bottles on the cradles and that the only way in which the cradles can be placed in vending position is through the positive action initiated by pressing the manipulating lever 172 as previously described.

However, if someone tampers with the machine by manually trying to force the rockers to oscillate without depositing a suitable coin, or if the drive mechanism is utilized with a different type of dispensing mechanism

which tends to be driven by the weight of the bottles rested thereon, the present invention is brought into play.

Assume that a clockwise torque, as viewed in Fig. 8, for example, is imposed on the vending control shaft 85. It is to be noted that the pawl 107 and ratchet wheel 105, and the clutch mechanism 140 do not act to prevent rotation in this direction.

Rotation of shaft 85 in a clockwise direction imposes a torsional force on the end 132 of the spring brake 130 in the groove 89 of the annular collar 88 thereby to tighten or constrict the spring around the collar. Frictional engagement of the spring on the collar has the same effect. The opposite end 131 of the spring is held relatively stationary on the bearing sleeve 76, because of its connection to the release member 115 which in turn is held against clockwise movement by the clutch mechanism 140. In effect, therefore, the opposite ends of the spring are twisted in opposite directions to clamp the spring tightly onto the collar 88, and bearing 76 thus to prevent rotation of the vending control shaft. It is to be noted that it is not absolutely necessary that the end 132 of the spring be connected to shaft 85 since it is found that sufficient friction exists between the spring and the collar to tighten the spring against the collar incident to clockwise rotation of the vending control shaft when the brake release member is held stationary.

Upon subsequent deposit of a proper coin and operation of the lever 172, the end 131 of the spring 130 is carried by the bracket 115 in unwinding direction during initial rotation of the shaft 151, so that by the time the pins 145 reach the ends of the slots 156 to establish driving connection with the shaft 85, the spring is expanded sufficiently to permit unimpeded turning on the bearing sleeve 76.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. In combination, a support, a drive mechanism including a bearing mounted in the support, a driven shaft rotatably mounted in the bearing, an elongated coil spring wound around the bearing and the shaft having an end outwardly extended adjacent to the bearing, the shaft normally being held against rotatable movement in a predetermined direction in the bearing by constriction of the spring therearound, a spring release member including a flange rotatably mounted on the bearing and connected to the end of the spring and an arm extended longitudinally of the shaft, said release member being adapted to expand the spring incident to rotation of the release member, a drive shaft rotatably mounted in support, and a clutch mechanism including a driven clutch member connected to the driven shaft and a driving clutch member connected to the drive shaft, the driving clutch member being successively engageable with the extended arm of the spring release member and with the driven clutch member incident to rotation of the drive shaft thereby initially to rotate the release member to expand the spring thereby freeing the driven shaft for rotation whereby subsequent interengagement of the drive and driven members effects rotation of the driven shaft by the drive shaft.

2. In combination with a support, a drive linkage adapted to interconnect a source of power and a driven mechanism so as to communicate motivating force from the source of power to the mechanism but to preclude independent operation of the source of power by said mechanism comprising a drive shaft rotatably mounted in the

support adapted for connection to said source of power; a bearing mounted in the support; a driven shaft rotatably mounted in the bearing in coaxial alignment with the drive shaft having a substantially cylindrical collar of substantially the same diameter as the bearing and endwardly adjacent to the bearing, the driven shaft being adapted for connection to said driven mechanism to drive such mechanism in response to rotation of the driven shaft in a predetermined direction; an elongated coil spring frictionally wound around the bearing and the collar in helical progression therearound in the same direction of rotation from the bearing to the collar as said predetermined direction for construction on the collar, the spring having an end extended, outwardly adjacent to the bearing; a bracket rotatably mounted on the bearing connected to said end of the spring for unwinding the spring incident to rotation of the bracket in said predetermined direction; and a clutch including drive and driven members respectively connected to the drive and driven shafts and releasably connected to each other for imparting rotation in said predetermined direction to the driven shaft incident to rotation of the drive shaft after a predetermined increment of rotation of the drive shaft, the drive clutch member being engageable with the bracket during said initial rotation of the drive shaft for rotating the bracket to unwind the spring thereby to precondition the driven shaft for rotation by the drive shaft.

3. In combination, a support; a substantially cylindrical sleeve bearing mounted in the support; a driven shaft journaled in the bearing having a substantially cylindrical collar rigidly thereon adjacent to the bearing and of substantially the same diameter as the bearing; a brake release member having a substantially U-shaped portion providing longitudinally spaced, parallel, substantially radial, mounting and adjusting plates individually rotatably fitted on the driven shaft, said mounting and adjusting plates being joined by an axially extended connecting plate, and the brake release member also including a substantially L-shaped portion providing a substantially radial adjusting plate rotatably fitted on the driven shaft and angularly adjustably secured to the adjusting plate of the U-shaped portion and an axially extended actuating arm extended from the adjusting plates in substantially parallel relation to the shaft in a direction away from the bearing; an elongated coil spring constituting a brake wound around the bearing and the collar on the driven shaft between the plates of the U-shaped portion of the brake release member adapted to be constricted on the collar thereby to brake rotation of the driven shaft in a predetermined direction, the spring having an end connected to the U-shaped portion of the brake release member and being wound in helical progression from the bearing to the collar in said predetermined direction of rotation; a driven clutch member mounted on the driven shaft; a drive shaft rotatably mounted in the support coaxially of the driven shaft; and a drive clutch member connected to the drive shaft releasably engageable with the actuating arm of the brake release member for rotating the brake release member in said predetermined direction incident to initial rotation of the drive shaft to expand the spring and precondition the driven shaft for rotation in said predetermined direction, the drive clutch member being engageable with the driven clutch member after said initial rotation of the drive shaft for imparting rotational movement to the driven shaft.

4. The combination of claim 3 wherein pegs are rigidly endwardly extended from the driven clutch member toward the drive clutch member in substantially parallel relation to the driven shaft and in substantially equally spaced relation circumferentially of the driven member; wherein the drive clutch member includes a plurality of arcuate slots in substantially equally spaced relation circumferentially of the drive member corresponding in

number and spacing to the pegs, the drive clutch member further having camming ramps extended endwardly outwardly from the drive clutch member away from the driven clutch member, each of the ramps being extended in the same direction circumferentially of the drive clutch member, the camming ramps being individually forwardly adjacent to the slots with reference to said predetermined direction of rotation whereby upon rotation of the drive clutch member in said predetermined direction, the pegs extend into the slots and engage the drive clutch member, the arm of the brake release member being extended into one of the slots of the drive clutch member for engagement by the drive clutch member during rotation thereof prior to engagement of the drive clutch member with the pegs, and whereby upon rotation of the drive clutch member opposite to said predetermined direction of rotation the pegs and the arm slidably ride against the camming ramps for free and independent rotation of the drive shaft relative to the driven shaft; and including means mounted on the drive shaft yieldably urging the drive clutch member toward the driven clutch member.

5. In combination with a support, a control mechanism comprising a bearing rigidly mounted in the support, a driven shaft rotatably mounted in the bearing, an elongated substantially tubular brake mounted in circumscribing overlapping relation on the shaft and the bearing normally frictionally constricted around the shaft and the bearing for resisting rotation of the shaft relative to the bearing, a brake release member rotatably borne by the support for rotation about an axis concentric to the driven shaft and connected to the brake for releasing the brake from constriction around the shaft incident to rotation of the release member so as to permit rotation of the shaft, a drive shaft rotatably mounted in the support, and means releasably connecting both the driven shaft and the brake release member to the drive shaft for rotating said release member to release the brake upon initial rotation of the drive shaft and for rotating the driven shaft upon further rotation of the drive shaft.

6. A drive linkage comprising a support; a bearing; means mounting the bearing in the support and holding the bearing against movement relative to the support, the bearing having an extended end providing an outwardly disposed substantially cylindrical periphery concentrically thereof; a driven shaft having a longitudinal axis of rotation, coaxially journaled in the bearing, and having an enlarged end extended from said end of the bearing, the enlarged end of the driven shaft having a cylindrical periphery continuous with the periphery of the bearing; a rotatable drive shaft having a longitudinal axis of rotation; means rotatably mounting the drive shaft in the support in axial alignment with the driven shaft; means connected to the drive shaft for oscillating the drive shaft about its axis of rotation; clutch means for interconnecting the drive shaft and the driven shaft and providing driving interconnection thereof only after a predetermined initial increment of rotation of the drive shaft in a predetermined direction; a helical spring frictionally circumscribing the peripheries of the end of the bearing and the enlarged end of the driven shaft for constriction thereon, said spring having an end on the bearing and an opposite end on the driven shaft and being wound in helical progression about said peripheries in the opposite direction of rotation from the shaft end to the bearing end from said predetermined direction of rotation from the shaft end to the bearing end from said predetermined direction of rotation of the drive shaft, the shaft end of the spring being connected to the driven shaft; and means

50 rotatably journaled on the bearing for rotation about said axis and having an extended end portion connected to the end of the spring on the bearing and an opposite end portion engageable with the clutch means during said initial increment of rotation of the drive shaft to unwind a portion of the spring during said initial increment of rotation and thereby to allow the drive shaft to rotate the driven shaft upon further rotation of the drive shaft.

7. In combination; a support; a driven shaft rotatably mounted in the support; a drive shaft rotatably mounted in the support in axial alignment with the driven shaft; a clutch including a pawl connected to the driven shaft and a ratchet wheel connected to the drive shaft and having a pair of circumferentially spaced slots, one of the slots loosely receiving the pawl so that an initial increment of rotation of the drive shaft is required before the wheel engages the pawl; a brake releasably engaging the support and the driven shaft to resist rotation of the driven shaft independently of the drive shaft; and brake release means rotatably carried by the driven shaft having an arm loosely extended into the other of the slots in the ratchet wheel and a flange connected to the brake, said brake release means being operable upon rotation thereof to release the brake, the wheel engaging the arm during said initial increment of rotation of the drive shaft and before engagement of the wheel and the pawl to rotate said means and release the brake from engagement with the driven shaft thereby to permit rotation of the driven shaft by the drive shaft upon further rotation of said drive shaft.

8. In combination, a support, a drive mechanism including a bearing mounted in the support, a driven shaft rotatably mounted in the bearing, an elongated coil spring wound around the bearing and the shaft having an end outwardly extended adjacent to the bearing, the shaft normally being held against rotatable movement in a predetermined direction in the bearing by constriction of the spring therearound, a spring release member including a flange rotatably mounted on the driven shaft and connected to the end of the spring and an arm extended longitudinally of the shaft, said release member being adapted to expand the spring incident to rotation of the release member, and a clutch mechanism including a driven clutch member connected to the driven shaft and a driving clutch member connected to the drive shaft, the driving clutch member being successively engageable with the extended arm of the spring release member and with the driven clutch member incident to rotation of the drive shaft thereby initially to rotate the release member relative to the spring thereby freeing the driven shaft for rotation whereby subsequent interengagement of the drive and driven members effects rotation of the driven shaft by the drive shaft.

9. In combination, a support, a bearing mounted in the support, a driven shaft having a longitudinal axis of rotation and being rotatably mounted in the support bearing for rotation about said axis, an elongated coil spring wound around the bearing and the shaft having an end adjacent to the bearing and an opposite end connected to the shaft, the shaft being normally held against rotatable movement in a predetermined direction in the support by constriction of the spring around the bearing and the shaft, a spring release member rotatably borne

5 by the bearing for rotation about the axis of the shaft, the release member having a flange connected to the end of the spring adjacent to the bearing and an arm extended longitudinally of the shaft, said release member being adapted to expand the spring incident to rotation of the release member about said axis, a drive shaft rotatably mounted in the support, and a clutch mechanism including a driven clutch member connected to the driven shaft and a driving clutch member connected to the drive shaft, the driving clutch member being successively engageable with the extended arm of the spring release member and with the driven clutch member incident to rotation of the drive shaft thereby initially to rotate the release member to expand the spring and thereby freeing the driven shaft for rotation whereby subsequent interengagement of the drive and driven members effects rotation of the driven shaft by the drive shaft.

10. In combination, a support, a drive mechanism including a bearing mounted in the support, a driven shaft rotatably mounted in the bearing, an elongated tubular diametrically expandable and contractible brake means circumscribing the bearing and the shaft so that the shaft is normally held against rotatable movement in a predetermined direction in the bearing by contraction of the brake means therearound, a brake release member including a flange rotatably mounted on the bearing and connected to the brake means for expanding the brake means incident to rotation of the flange on the bearing in said predetermined direction, the brake release member also including an arm extended longitudinally of the shaft, a drive shaft rotatably mounted in the support, and a clutch mechanism including a driven clutch member connected to the driven shaft and a driving clutch member connected to the drive shaft, the driving clutch member being successively engageable with the extended end of the brake release member and with the driven clutch member incident to rotation of the drive shaft thereby initially to rotate the release member to expand the brake means and thereby freeing the driven shaft for rotation whereby subsequent interengagement of the drive and driven members effects rotation of the driven shaft by the drive shaft.
